UNITED STATES PATENT OFFICE.

WILLIAM S. DUFFIELD, OF HAMILTON, ONTARIO, CANADA.

INSTEP-ARCH SUPPORTER.

Application filed December 4, 1925. Serial No. 73,203.

This invention relates to supports to be used in shoes to support broken down instep arches, and my object is to provide a light, strong support which can be made in effect a part of the shoe and which can be readily adjusted to suit the instep of the wearer's foot.

I attain my object by means of a screw for variably flexing an arch member so that the height of the latter may be varied relative to the insole of the wearer's shoe. The constructions are hereinafter more fully described and illustrated in the accompanying drawings in which—

15 Fig. 1 is a side elevation, partly in section, of a shoe showing my device therein;

Fig. 2 a cross section of the same;

20 Fig. 3 a plan view of a modified form of my device; and

25 Fig. 4 a cross sectional detail of the arch member shown in Fig. 3.

In the drawings like numerals of reference indicate corresponding parts in the different figures.

25 1 is a flexible arch member formed of tempered leather which is curved transversely to follow the transverse contours of the wearer's foot according to approved practice in the arch support art. The arch member is also curved longitudinally to follow the contours of an average instep arch of a wearer's foot. As hereinafter described, this curvature may be varied to suit the particular condition of the wearer's instep arch.

The member 1 is reduced in thickness from the middle towards each end 1^a and its ends are skived and suitably secured to an insole 2. It will be distinctly understood that the term "insole" means either a removable or fixed leather insole and that it includes a thin metallic plate adapted to be inserted in a shoe and rested on the insole or outer sole thereof. In practice the ends 45 1^b are secured by rows of stitching 3 to a leather insole. The end stitches of each row are looped round the sides of the member to securely fasten the latter to the insole. A wearing plate 4 carried on the upper surface of the insole 2 is secured thereto by means of prongs 5 formed integral with the plate.

To the underside of the arch member 1 is secured a nut 6 formed as a thin plate.

55 This plate is provided with integral prongs

7 adapted to be pressed into the arch member to secure it to the latter. A screw 8, passed through a hole 9 formed in the member 1 and threaded through the nut 6, is adapted to engage the wearing plate 4. As 60 the screw is turned in either direction the arch will be variably flexed so that its height will be varied to suit the instep arch of the wearer's foot. The screw 8 may be either a grub or a set screw. If the latter type is 65 used the hole 9 will be of larger diameter than the diameter of the head of the screw. This permits a socket wrench or key to be inserted in the hole to adjust the screw. It is obvious that various lengthed screws may 70 be used in adjusting the device so that the screw head will not project beyond the upper surface of the arch member.

An insole lining 10 covers the opening in the arch support and provides a smooth 75 surface for the wearer's foot.

To reinforce the leather arch member 1, I provide its underside with a very thin metal supporting strip 11. This strip is suitably secured to a plate 6^a serving as a 80 nut and extends laterally thereof to support the upwardly curved side or sides 1^a of the member 1.

What I claim is:

1. An instep arch supporter comprising 85 an insole; a wearing plate carried on the upper surface of the insole; a leather flexible arch member secured at one end to the insole and convexly curved longitudinally and concavely curved transversely at its middle portion; a nut carried on the underside of the said member; and a screw threaded through the nut and adapted to engage the wearing plate to flex the leather arch member, the said arch member having an opening 90 therethrough for the passage of the screw, the opening being of sufficient diameter to permit adjustment of the latter by a tool.

2. An instep arch supporter comprising 100 an insole; a leather flexible arch member having its ends skived and resting on the insole and formed with an upwardly curved side; a transverse metal strip beneath the middle of the arch member for supporting the said curved side; a screw threaded 105 through said metal strip; and a wearing plate on the insole engageable by the screw to variably flex the arch member, which is secured at one end to the insole.

3. An instep arch supporter comprising 110

an insole; a wearing plate carried on the upper surface of the insole; a leather flexible arch member carried on the insole secured at each end to the insole and formed with

5 an upwardly curved side; a transverse metal plate serving as a nut beneath the middle of the underside of the said member for

supporting the said curved side; and a screw threaded through the plate nut and adapted to engage the wearing plate.

Signed at Hamilton, Canada, this first day of Dec., 1925.

10

WILLIAM S. DUFFIELD.
